UNITED STATES PATENT OFFICE.

PHILIP STEVENS, OF TOLEDO, OHIO.

DESIGN FOR A SIGN-LETTER.

SPECIFICATION forming part of Design No. 25,156, dated February 11, 1896.

Application filed July 14, 1893. Serial No. 480,536. Term of patent 7 years.

To all whom it may concern:

Be it known that I, PHILIP STEVENS, a citizen of the United States, residing at Toledo, county of Lucas, and State of Ohio, have invented and produced a new and original Design for a Sign-Letter, of which the following is a specification, reference being had to the accompanying drawings, showing a part thereof.

Figure 1 is an elevation of a sign-letter, illustrating my design; and Fig. 2 is a sectional view of the same.

The leading feature of my design consists in the body of the letter and a beveled portion extending at an angle thereto, said beveled portion being of two planes, whereby the combined body and bevel present three planes and when viewed in elevation form a varied shading.

1 designates the sign-letter, comprising a body 2 having a plain face, and 3 designates the bevel extending from the body at two angles, as shown, whereby the shade effect of the sign-letter is heightened, due to the form of the bevel.

What I claim is—

The design for a sign-letter substantially as herein shown and described.

In testimony that I claim the foregoing as my own I hereby affix my signature in presence of two witnesses.

PHILIP STEVENS.

Witnesses:

WILLIAM WEBSTER,
F. R. WEBSTER.
